INSULATOR BRACKET

Archibald T. Flower, Jenkintown, Pa.

Application November 21, 1936, Serial No. 112,137

6 Claims. (Cl. 173—321)

This invention relates to an improved insulator bracket particularly adapted for attaching insulators to the brick or stone walls of a building for supporting electrical conduits, cables and the like.

It is an object of the invention to provide an insulator bracket which may be firmly and securely anchored in the seam or joint of a wall of masonry during the course of construction.

10 A further object of the invention resides in providing a bracket of great strength made from a minimum amount of material and which facilitates the proper spacing of the insulators from the wall and from each other.

15 Another object of the invention resides in providing a bracket which is simple and durable in construction, efficient in operation and inexpensive to manufacture.

Other objects and advantages of the invention 20 will be apparent during the course of the following description.

In the accompanying drawing, forming a part 25 of this specification and in which like numerals are employed to designate like parts throughout the same,

Fig. 1 is a perspective view of the bracket applied to a brick wall.

Fig. 2 is a longitudinal sectional view of the 30 bracket shown in Fig. 1, and,

Fig. 3 is a section taken on line 3—3 of Fig. 2.

In the drawing, wherein for the purpose of illustration, I have shown a preferred embodiment of my invention, the bracket 5 is formed by bending a flat strip of metal, intermediate its 35 length, to provide spaced parallel arms 6 having their free ends bent in opposite directions at right angles to the body of the arms to provide stop lugs 7. When installed in a brick wall, the arms 6 are disposed in straddling relation to one or 40 more courses of brick 8 and are positioned to bridge a vertical seam or joint 9 of the course of bricks above and below the bracket. The stop lugs 7 engage against the inner side of the wall limiting the longitudinal movement of the bracket. The arms 6 at a point between the 45 inner and outer sides of the wall are provided along their medial line with oppositely bent tangs 10 which enter the vertical seams of the adjacent courses of brick between the ends of the bricks in the front row of the course, to prevent side or lateral movement of the brackets. The bent portion 11 of the bracket is curved and has a central opening to receive a bolt 12 for supporting an insulator 13 at the extreme forward 55 end thereof. The arms 6 adjacent the forward

end of the bracket are provided with aligned openings 14 for passing a bolt 15 therethrough on the ends of which are mounted insulators 16. Additional openings are provided in the arms to permit the proper spacing of the insulators from the wall and if desired an insulator may be mounted on the bolt 15 between the arms 6. Also a cable clamping clip 17 may be attached to the upper arm of the bracket adjacent the outer side of the wall by means of a bolt 18.

In use, the bracket is installed in the wall of the building during the course of construction and forms an integral part thereof which prevents accidental displacement of the bracket. When applying the bracket, the arms 6 are 15 positioned to straddle a course of bricks at a point to bridge one of the vertical transverse seams of the course of bricks above and below the bracket, so that the tangs 10 project into the vertical seams between the ends of the bricks 20 in the front row, thereby preventing lateral movement of the brackets when the wires supported by the bracket are pulled taut. The free ends of the arms are positioned so the stop lugs 25 engage against the inner side of the wall and prevent longitudinal movement of the brackets.

It is to be understood that the form of my invention herein shown and described is to be taken as a preferred example of the same and that certain changes in the shape, size and arrangement of the parts may be made without departing from the spirit of the invention or the scope of the subjoined claims.

Having thus described my invention, I claim:

1. An insulator bracket for attachment to a 35 masonry wall formed of a single strip of flat metal bent substantially U-shape to provide spaced parallel arms and tangs extending from said arms at an angle thereto for anchoring said strip in the wall.

2. An insulator bracket for attachment to a wall formed of a single strip of flat metal bent intermediate its length to provide spaced parallel arms, adapted to extend through seams of the wall, the free ends of said arms being bent 45 at an angle to form stop lugs and tangs extending from said arms at an angle thereto for anchoring the arms in the wall.

3. An insulator bracket for attachment to a masonry wall comprising a flat metal strip bent 50 intermediate its length to form spaced parallel arms, a portion of each of said arms being adapted to pass through respective seams of the wall, and means for supporting insulators on the portion of said arms extending beyond the wall. 55

4. An insulator bracket for attachment to a masonry wall formed of a single strip of flat metal bent substantially U-shape to provide spaced parallel arms, the free ends of said arms being adapted to pass through respective horizontal seams of the wall in bridging relation to a transverse vertical seam of the wall, and tangs struck from said arms adapted to enter the transverse vertical seam of the wall.
5. An insulator bracket for attachment to a masonry wall formed of a single strip of flat metal bent substantially U-shape to provide spaced parallel arms adapted to extend through respective horizontal seams of the wall, the free ends of said arms being bent in opposite direc-
- 10 tions adapted to engage the adjacent face of the wall, and tangs struck from said arms intermediate their length adapted to engage in a vertical seam of said wall.
6. An insulator bracket for attachment to a masonry wall formed of a single strip of flat metal bent substantially U-shape to provide spaced parallel arms adapted to extent through respective horizontal seams of the wall, tangs struck from said arms adapted to engage a vertical seam of the wall, and means passing through said arms adjacent the bend of the strip for attaching insulators thereto.
